UNITED STATES PATENT OFFICE.

ADOLPH K. MALMQUIST, OF SOUTH BELLINGHAM, WASHINGTON, ASSIGNOR TO MALMQUIST MACHINE COMPANY, OF SOUTH BELLINGHAM, WASHINGTON.

LUBRICATING MEANS.

Application filed March 18, 1925. Serial No. 16,433.

This invention relates to improvements in lubricating means and more particularly to such as are adapted for use and in co-operation with canning apparatus.

5 In certain canning apparatus, a pocketed carrier is provided and adapted to rotate within a casing, the pockets of said carrier forming vacuum filling chambers in which cans or containers are filled with liquid, 10 usually syrup. Such apparatus is disclosed in my copending applications Serial Nos. 582,712 and 734,224. It is important that the free rotation of the rotary pocketed carrier shall not 15 be interrupted or interfered with, but it may sometimes happen that spilled syrup may find its way to the bearing surface between the carrier and its casing and interfere with the free movement of the carrier. The 20 object of my present invention is to provide simple and efficient means whereby the outer bearing surface of the rotary carrier may be kept clean and lubricated.

With this object in view, the invention 25 consists in certain novel features of construction and combinations of parts as hereinafter set forth and pointed out in the claims.

In the accompanying drawings;

30 Figure 1 is a view partially in plan and partially in section illustrating an application of my invention;

Figure 2 is an enlarged vertical sectional view of the lubricator;

35 Figures 3 to 8 are views illustrating details, and

Figure 9 is a view in section on the line 9-9 of Figure 2.

In Figure 1 of the drawing is shown a 40 fragmentary part of the can filling mechanism of canning apparatus, said mechanism including a casing 1 and a rotary pocketed carrier 2, the pockets of which form liquid filling chambers, and near the inlet opening

45 3 of the casing, a rotary feeding device 4 is located for moving cans through the opening 3 to the pockets of the rotary carrier, all as fully disclosed in my copending applications hereinbefore identified.

50 The feeding device 4 is carried by a vertical shaft 5 provided with a gear 6 to which motion is applied from suitable driving mechanism, and this same shaft 5 carries my improved lubricating device 8.

55 In constructing the lubricating device, a

frame 9 is mounted on the feeder 4 and includes two parallel frame plates 10 and 11 spaced apart and the plate 11 is provided with a central elongated enlargement 12 entering a recess 12^a in the plate 10 and 60 having an opening 13 through the same, the frame plates being secured together by means of bolts 14 passing through the enlargement 12 on one of said plates and entering the other plate. 65

Holders 15 and 16 having guide ribs 17, 18 are movable between the frame plates 10, 11 at respective sides of the enlargement 12. The holders 15 and 16 carry felt wipers 19, 20, and said holders are normally pressed outwardly by means of a spring 21 passing through the opening 13. The movements of the holders and the wipers carried thereby are limited by bolts 22, 22 carried by the frame 9 and passing through 75 enlarged holes 23, 23, in said holders as clearly shown in Figures 2 and 9.

The holder 15 carries a receptacle 24 for lubricant, and this receptacle discharges lubricant (water or oil), through ducts 25, 26 80 to the felt wiper 19, and the holder 16 carries a lubricant receptacle 27 (made annular in form and encircling the receptacle 24) is movably mounted on the holder 15 and is adapted to discharge lubricant, through 85 ducts 28, 29 to the wiper 20.

It is apparent that as the lubricator and the pocketed carrier rotate as indicated by the arrows in Figure 1, the wipers, projecting through the entrance opening 3 in the 90 casing 1, will wipe and lubricate the outer face of the rotating carrier.

Various changes might be made in the details of construction of my invention without departing from the spirit of the latter 95 or limiting its scope and hence I do not wish to restrict myself to the precise details herein set forth.

Having fully described my invention what I claim as new and desire to secure 100 by Letters Patent, is:-

1. In lubricating means, the combination with a frame, of holders movably mounted therein, wipers carried by said holders, spring means between said holders exerting 105 outward pressure against the same, lubricant supply means, and means for conducting lubricant from said lubricant supply means to said wipers.

2. In lubricating means, the combination 110

with a revoluble frame, of two holders slidingly mounted therein and each having a transverse hole, wipers carried by said holders, lubricant receptacles carried by the respective holders, means for conducting lubricant from said receptacles to said wipers, a spring between said holders, and bolts carried by the frame and passing through the transverse holes in the holders, each of said bolts being appreciably less in diameter than that of the hole through which it passes.

3. In lubricating means, the combination of a revoluble frame comprising spaced plates and an inwardly projecting per-

forated enlargement on one of said plates, holders guided between said plates at respective sides of said enlargement, lubricant receptacles supported on said frame, wipers carried by said holders, said holders having passages to conduct lubricant from said receptacles to said wipers, and a spring passing through said perforated enlargement and pressing at its respective ends against said holders.

In testimony whereof, I have signed this 25 specification.

ADOLPH K. MALMQUIST.
